WILLIAM W. BURKE, OF BENNINGTON, VERMONT, ASSIGNOR OF ONE-FOURTH TO
JAMES E. BURKE AND ONE-FOURTH TO ALEXANDER J. COOPER, BOTH OF BEN-
NINGTON, VERMONT.

STOP-MOTION FOR KNITTING-MACHINES.

1,096,890.

Specification of Letters Patent. Patented May 19, 1914.

Application filed May 10, 1913. Serial No. 766,685.

To all whom it may concern:

Be it known that I, WILLIAM W. BURKE, a citizen of the United States, residing at Bennington, in the county of Bennington 5 and State of Vermont, have invented new and useful Improvements in Stop-Motions for Knitting-Machines, of which the following is a specification.

This invention relates to an electric circuit 10 closing device particularly adapted to be used in machines employing a thread or a strand of yarn, such as knitting machines, said device embodying in its construction a drop device which is adapted to open and 15 close said electric circuit, the device being so constructed and arranged that when a thread or yarn breaks, or when abnormal tension is brought to bear upon said thread or yarn, the drop device will be operated to 20 close the circuit. Said circuit comprises an armature and an electromagnet, the armature being mounted upon a tripper forming a part of a stop motion device which is so constructed that when the circuit is closed 25 and the armature drawn toward the magnets of the electromagnet, said tripper will operate to release the stop motion mechanism and allow the same to operate to move the belt from the tight pulley to the loose pulley 30 on the driving shaft and thus stop the machine.

In the embodiment of my invention hereinafter described I have shown my improved electric circuit closing device in connection 35 with a knitting machine and a stop motion therefor, but the same is adapted to be used in any machine employing a strand of yarn or a thread in which it is desirable to have the machine stop when the thread breaks or 40 the supply from the mass of thread runs out or when abnormal tension is applied to said thread or yarn.

In the preparation of yarn for use in a knitting machine for knitting a fabric, the 45 same is ordinarily run through a winding machine in which the yarn is taken from a thread mass, known as a "cone," and is passed through a scraper which removes the superfluous yarn and detects any large knots 50 and stops the feed of the yarn from the cone when such large knots occur, said yarn passing from the cone to the scraper and from the scraper to a bobbin upon which it is wound and these bobbins, with the yarn

wound thereon, are then used to supply yarn 55 to a knitting machine. By my improved circuit closing device, in combination with a scraper interposed between said circuit closing device and a cone of yarn, superfluous waste is removed from the yarn and yarn 60 with large knots prevented from feeding to the knitting instrumentalities without first passing the yarn through a winding machine, as hereinbefore described, prior to using the same in a knitting machine, and thus one operation and machine is eliminated, whereby a large amount 65 of time and expense is saved.

The object of this invention, therefore, is to embody in a knitting machine a yarn 70 scraper for removing the superfluous yarn from a strand of the same as it is being fed into said machine, said scraper also being so adjusted as to prevent the passage of yarn into a machine when a large knot occurs in 75 the yarn, and to combine with said scraper an electric circuit closing device of the character hereinbefore set forth together with a stop motion mechanism, all so arranged and constructed that the machine will be stopped 80 immediately when a thread or yarn breaks or when abnormal tension is brought to bear upon said thread or yarn or when the supply of thread or yarn runs out.

The invention consists in the combination 85 and arrangement of parts set forth in the following specification and particularly pointed out in the claims thereof.

Referring to the drawings: Figure 1 is a plan view, partly in section and broken 90 away, of a stop motion mechanism for a knitting machine with my improved electric circuit closing device attached thereto. Fig. 2 is a detail sectional elevation taken on line 2-2 of Fig. 1. Fig. 3 is a perspective 95 view of the electric circuit closing device. Fig. 4 is a plan view of said electric circuit closing device. Fig. 5 is a front elevation of the electric circuit closing device with the parts in their normal position when the 100 yarn is feeding to the machine. Fig. 6 is a front elevation of the electric circuit closing device similar to Fig. 5, partly broken away and shown in section and with the parts in the position assumed thereby when 105 abnormal tension is applied to the yarn. Fig. 7 is a detail end elevation of the circuit closing device as viewed from the left

of Fig. 5. Fig. 8 is a sectional elevation taken on line 8—8 of Fig. 4. Fig. 9 is a detailed end elevation of the circuit closing device as viewed from the right of Fig. 5. Fig. 10 is a rear elevation of the stop motion mechanism with parts broken away to save space in the drawings. Fig. 11 is a front elevation of a modified form of circuit closing device with means for cutting off the yarn attached thereto. Fig. 12 is a sectional elevation taken on line 12—12 of Fig. 11. Fig. 13 is a front elevation of the circuit closing device with another form of means for cutting off the yarn attached thereto.

Like numerals refer to like parts throughout the several views of the drawings.

In the drawings, referring to Figs. 1 to 10 inclusive, 15 is the frame of the machine consisting of side standards 16 and 17 suitably connected together by a cross head 18. The main driving shaft 19 is journaled to rotate in bearings 20 and 21 fast to the frame of the machine and is rotated by means of a pulley 22 fast to the shaft 19, a loose pulley 23 being journaled to rotate upon the shaft 19 adjacent to the pulley 22. The pulley 22 is driven by means of a belt 24. A bevel gear 25 is fastened to the main driving shaft 19 and meshes into another bevel gear 26 fast to a vertical shaft 27, said vertical shaft being utilized for rotating the needle cylinders 28 and 29, Fig. 2. The manner in which these needle cylinders and co-acting parts are constructed, and operated from the shaft 27 is clearly described and shown in patent to William T. Barratt No. 1,000,362 dated August 15, 1911, stop motion for knitting machines, to which reference may be had.

The stop motion mechanism is illustrated particularly in Figs. 1, 2 and 10. Referring now to these figures it will be seen that a wheel 30 is journaled to rotate upon a stud 31 fast to a bracket 32 which is, in turn, fastened to the cross head or tie 18. An arm 33 is pivoted at 34 to the wheel 30 and is held against a stop screw 35 by a spiral spring 36. A plurality of these arms 33 and mechanism connected thereto may be used in connection with the wheel 30, but as they all operate in substantially the same manner the following description of the mechanism connected with one of said arms will be sufficient. A rod 37 is pivotally connected at 38 to the wheel 30. Said rod is arranged to slide in a bracket 39 fast to the cross head 18. The free end of the rod 37 bears against an arm 40 which is fast to a rock-shaft 41 arranged to rock in ears 42 on the frame of the machine. Handles 43 are fastened to said rock-shaft by means of which the same may be operated to ship the belt and stop the machine by hand. A tripper arm 44 is also fastened to said rock-shaft and is provided with a notch 45 in its free end and

adapted to engage the free end of an arm 46 which is fastened to a rod 47 arranged to slide in bearings formed in brackets 48 fast to the cross head 18. A spiral spring 49 encircles the rod 47 and is interposed between the arm 46 and one of the brackets 48, said spring tending to move the rod 47 toward the left (Fig. 10). Shipper arms 50 are fast to the rod 47 and are adapted to engage therebetween the belt 24. It will be evident that when the shaft 41 is rocked to disengage the tripper arm 44 from the arm 46 the rod 47 will be moved to shift the belt from the fast to the loose pulley, thus stopping the machine. Said rod 47 is adapted to be operated to stop the machine by a tripper mechanism which I will now proceed to describe.

A dog 51, constituting a tripper, is fastened to a vertical shaft 52 and is constructed to engage a notch 53 in the end of the arm 33, so that when the shaft 52 is rocked toward the right (Fig. 1), the arm 33 will be disengaged from the dog 51 and the stop motion will be actuated to stop the machine as hereinbefore described. The shaft 52 is rotatably mounted upon the bed plate 54 and is rotated by a spring 55 in a direction to bring a pin 56 fast to said shaft against a bracket 57 in the lower end of which the shaft 52 is rotatably mounted. The shaft 52 is rotated in the opposite direction to that in which it is rotated by the spring 55, or toward the right (Fig. 1), to disengage the dog 51 from the arm 33 by an armature lever 58 which is actuated by an electromagnet 59 forming a part of an electric circuit 60. The electromagnet 59 is fastened to the cross head 18 and is connected by an electric wire 61 (see Fig. 1) to one of the terminals 62 of the circuit closing device 63. The other terminal 64 of said circuit closing device is connected by a wire 65 with a battery 66 from which a wire 67 leads to a binding screw 68 on the armature lever 58. The free end of the armature lever 58 normally contacts with a metal plate 69 which is connected by a wire 70 with the electromagnet 59.

The circuit closing device 63 has a base 71 which is fastened to the cross tie 18 and on said base is mounted a block 72 of insulating material in which is slidably mounted a drop device 73 consisting of a wire bent in U-shape, the legs 74 constituting contact points and the closed end being bent at 75 to form a guide for a strand of yarn 76. When said strand of yarn breaks or the supply runs out or when an abnormal tension is applied thereto, the legs 74, 74 will be caused, in a manner hereinafter described, to engage the contacts 77 which preferably consist of mercury inclosed in chambers 78 within the base 71. When the circuit is open the parts will be in the position illus-

trated in Fig. 1. When the circuit is closed by the drop wire 73 the electromagnet 59 will be energized and the armature 58 drawn toward the same to rock the shaft 52 and dis-
5 engage the drop dog 51 from the end of the arm 33, whereupon the stop motion mech-
anism will be actuated, as hereinbefore de-
scribed, to move the belt 24 from the fast
pulley 22 to the loose pulley 23 and thus stop
10 the machine.

Referring now to the circuit closing de-
vice illustrated in Figs. 3 to 9 inclusive, the
drop wire 73 is held out of contact with the
contacts 77 by the strand of yarn 76 which
15 passes from a yarn mass 79 through a guide
eye 80 provided in the auxiliary frame 81,
through a yarn scraper 82 to the guide eye
or bend 75 formed in the drop wire 73,
thence upwardly through a stationary guide
20 eye 83, through a movable guide eye 84 and
through stationary guide eyes 85, 85' 86
and 87 to the primary needles of the knitting
machine. The scraper 82 consists of two
scraper blades 89 and 90 fastened by screws
25 91 and 92, respectively, to the block 72. The
screws 91 and 92 pass through slots 93 and
94, respectively, in the blades 89 and 90, so
that said blades can be adjusted vertically
or one can be adjusted toward the other to
30 vary the space 95 between their adjacent
edges. A cross-bar 96 is fastened to the
blade 89 and forms a stop to prevent the
waste of yarn from passing upwardly
35 through the blades 95 and becoming entan-
gled in the circuit closing mechanism located
beyond said scraper. A bar 97, preferably
of porcelain, is fastened to the blade 89 and
constitutes a guide for the thread and by
40 raising and lowering the blade 89 the drop
wire 73 and its legs 74 will be raised or
lowered to move said legs or contact points
away from or toward the mercury contacts
77. The guide eye 83 is stationary and is
45 fastened to the block 72 and in such a po-
sition relatively to the drop device that the
thread or yarn 76, as it passes from the guide
75 to the guide 83, will be held in a substan-
tially vertical direction. The object of this
50 construction is to prevent the vibration of
the thread while it is being fed into the ma-
chine, which vibration would occur if the
thread extended in a substantially horizontal
instead of a vertical direction from the drop
device to the thread guide 83, but when the
55 thread is laid in a vertical direction this vi-
bration of the thread is prevented. A vibra-
tion of the thread or yarn would lead to the
contact points 74 making accidental contact
with the mercury contacts 77 when the
60 thread had not broken or when abnormal
tension was not applied thereto, which would
render the device inaccurate and unreliable.

The movable guide eye 84 is fastened to a
65 U-shaped lever 98 pivoted at 99 to the block
72. This lever has an arm 100 thereon which

projects over the closed end of the U-shaped
drop wire 73 and forms a stop therefor to
prevent said wire from being moved away
from the contacts 77 more than a certain
70 distance. This distance can be regulated
by an adjusting screw 101 which has screw-
threaded engagement with the lever 98 and
is adapted to engage the block 72, so that by
75 turning said screw in one direction or the
other, the free end of the arm 100 will be
raised or lowered and thus the position of
the drop wire 73 determined.

The lever 98 is provided with pins 102
upon which may be placed slotted plates 103
in order to apply the proper tension to the
80 yarn 76 to hold the lever 98 downwardly in
substantially the position illustrated in Fig.
5 with the screw 101 in contact with the
block 72 under normal conditions or when
the yarn is subjected to a normal tension.
85 Different sizes of yarn require more tension
and for larger sizes two or more plates may
be placed upon the pins 102. In practice the
weight of the lever 98 is sufficient for certain
90 sizes of yarn; then a plate 103 is placed on
the pins 102 for larger sizes and another
plate 103 is placed on the pins 102 for still
larger sizes, making it necessary to employ
only two plates for all sizes of yarn ordi-
narily used in knitting machines. The drop
95 wires 73 are also made of different sized wire
in order to drop quickly and have the con-
tact points 74 engage the mercury contacts
77 without loss of time when the yarn breaks,
as, for instance, when the yarn breaks be-
100 tween the drop wire 73 and the needles it is
necessary that the drop wire should be heavy
enough to pull the weight of the yarn left
between said drop wire and the broken end
of the yarn without delay and for a heavier
105 yarn it takes a heavier drop wire than for
a light yarn to perform this function.
Therefore, three sizes of drop wires are uti-
lized for all sizes of yarn ordinarily used in
a knitting machine.

The general operation of the mechanism
hereinbefore specifically described is as fol-
lows: Assuming a knitting machine to be
in operation and the parts to be in the rela-
tive positions illustrated in Figs. 1, 2, 3,
115 4, 5 and 8, it will be seen that the drop wire
73 is raised by the tension of the yarn 76,
so that the contact points 74 are out of con-
tact with the contacts 77 and therefore, the
electric circuit 60 is open. The guide 97
120 is at such a height relatively to the drop
wire 73 and the arm 100 is in such a posi-
tion relatively to said drop wire that the
contact points, while close to the contacts 77,
do not engage the same. The adjusting
125 screw 101 upon the lever 98 contacts with
the block 72 at its lower end. The yarn
extends in substantially a horizontal direc-
tion from the guide 97 to the guide 75 of
the drop wire 73; then said yarn 76 ex-

tends in a substantially vertical direction to the guide eye 83 for the reason hereinbefore set forth, viz., to prevent vibration of the yarn during the operation of the machine and accidental contact of the drop wire with the contacts 77. From the guide eye 83 the yarn extends through the guide eye 84 and from the guide eye 84 to the guide eye 85 in such a direction as to form a bight, (see Fig. 5). The reason for this arrangement is that when an abnormal tension is applied to the yarn the lever 98 will move upwardly from the position illustrated in Fig. 5 to that illustrated in Fig. 6. At the same time the arm 100 will positively push the drop wire 73 downwardly to engage the contacts 77 and close the electric circuit. When the wire 73 is thus pushed downwardly by the arm 100, it is evident that yarn must be paid out to said drop wire or the device will become locked and by the arrangement hereinbefore set forth by which a bight is obtained in the thread 76 adjacent to the thread guide 84 this yarn can be paid out to a sufficient extent so that no locking of the mechanism by said yarn will occur. Thus, when abnormal tension is applied to the yarn it will be understood that the lever 98 will be rocked on its pivot from the position illustrated in Fig. 5 to that illustrated in Fig. 6 and the arm 100 will force the wire 73 downwardly until the contact points 74 engage the contacts 77 and complete the circuit. As soon as the circuit is completed the armature lever 58 will be drawn toward the magnet 59, causing the shaft 52 to rock and the tripper 53 to release the arm 33, whereupon the spring 36 will move the arm 33 and the wheel 30 so as to move the rod 37 to cause the arm 44 on the rock-shaft 41 to become disengaged from the yarn 46, whereupon the spring 49 will cause the rod 47 to move the shipper arms 50, thus moving the belt from the fast to the loose pulley and stopping the machine. If the yarn should break, then the drop wire 73 will, of its own weight, drop until the contact points 74 engage the contacts 77, completing the circuit and causing the stop motion mechanism to be operated as hereinbefore described. The same would be true if the supply of yarn ran out.

It will be understood that one of the circuit closing devices hereinbefore described will be supplied for each feed of yarn in a knitting machine and also that the circuit closing device is applicable to any machine employing a strand of thread or yarn for the purpose of closing an electric circuit to operate a stop motion when the tension becomes abnormal upon said thread or yarn or when the thread or yarn breaks or when the supply of thread or yarn runs out.

In Figs. 11 and 12 a modification of my invention is illustrated which includes in

addition to the mechanism hereinbefore described as constituting a circuit closing device a mechanism for cutting the yarn. Referring to these figures, 82 is the scraper, 72 the block, 71 the base, 83 the stationary thread guide, 84 the movable thread guide, 98' the lever to which the movable thread guide 84 is fastened, said lever being pivoted at 99 to the block 72. The lever 98' has an arm 104 which is connected by a link 105 to a movable cutter arm 106 pivoted at 107 to the stationary cutter 108. The stationary cutter 108 is fastened to the scraper blade 90. When abnormal tension is applied to the yarn, the lever 98' will be actuated as hereinbefore described and will be rocked upon its pivot 99, causing the arm 104 to descend and through the link 105 the movable cutter 106 will be rocked upon its pivot 107 to coact with the stationary cutter 108 and sever the yarn, whereupon the drop wire will descend and close the circuit and the machine will be stopped by the stop mechanism as hereinbefore described.

In Fig. 13 a modification of the cutting mechanism is illustrated in which the lever 109, corresponding in function to the lever 98, has an arm 110 thereto to which a cutter 111 is fastened, said cutter being adapted to coöperate with a stationary cutter 112 fast 95 to the scraper blade 90. When the lever 109 is rocked by abnormal tension on the thread 76 which is guided by the guide eyes 83 and 84, as hereinbefore described, said movable cutter will be caused to engage the yarn 76 100 and coöperating with the stationary cutter 112 will sever said yarn, whereupon the drop wire 73 will descend and close the circuit, thus causing the stop motion to be operated to stop the machine, as hereinbefore de- 105

It will be understood that when the armature lever 58 is drawn toward the magnet 59, as hereinbefore described, when the circuit is closed, the free end of said armature 110 lever 58 will move along the insulated plate 69 until the armature lever is within close proximity to the magnet 59, whereupon the free end of said armature lever will slide off of the plate 69 onto the block of insulating material 69'. Thus the stop motion mechanism will be actuated, as hereinbefore described, and the circuit will be left broken by reason of the armature lever 58 finally coming to rest with its free end on the insulating plate 69', whereby the electric circuit will be finally broken and thus the batteries will not be run down.

Having thus described my invention, what I claim and desire by Letters Patent to 125 secure is:

1. A circuit closing device having, in combination, an electric circuit including a drop device adapted to open and close said circuit and constituting a guide for a strand of 130

yarn, a plurality of guides for said yarn and means actuated by an abnormal tension on said yarn adapted to engage said drop device and move it to close said circuit.

5. 2. A circuit closing device having, in combination, an electric circuit including a drop device adapted to open and close said circuit and constituting a guide for a strand of yarn, a plurality of guides for said yarn, a lever adapted to engage said drop device and a guide for said yarn mounted on said lever whereby, when under abnormal tension, said lever may be rocked by said yarn to move said drop device to close said circuit.

10. 3. A circuit closing device having, in combination, an electric circuit including a drop device adapted to open and close said circuit and constituting a guide for a strand of yarn, a stationary guide for said yarn at one side of said drop device, a movable guide for said yarn on the opposite side of said drop device and means connected with said movable guide and engaging said drop device adapted to be actuated by an abnormal tension on said yarn to move said drop device to close said circuit.

15. 4. A circuit closing device having, in combination, an electric circuit including a drop device adapted to open and close said circuit and constituting a guide for a strand of yarn, a stationary guide for said yarn at one side of said drop device, a movable guide for said yarn on the opposite side of said drop device, another yarn guide interposed between said movable guide and said drop device and means connected with said movable guide and engaging said drop device adapted to be actuated by an abnormal tension on said yarn to move said drop device to close said circuit.

20. 5. A circuit closing device having, in combination, an electric circuit including a drop device adapted to open and close said circuit and constituting a guide for a strand of yarn, a stationary guide for said yarn at one side of said drop device, a movable guide for said yarn on the opposite side of said drop device, another yarn guide interposed between said movable guide and said drop device and elevated above said movable guide and drop device and means connected with said movable guide and engaging said drop device adapted to be actuated by an abnormal tension on said yarn to move said drop device to close said circuit.

25. 6. A circuit closing device having, in combination, an electric circuit including a drop device adapted to open and close said circuit and constituting a guide for a strand of yarn, a plurality of guides for said yarn, a lever adapted to engage said drop device, a pivot for said lever, means to vary the weight of said lever at one side of said pivot and a guide for said yarn mounted on said lever whereby when under abnormal tension

said lever may be rocked by said yarn to move said drop device to close said circuit.

7. A circuit closing device having, in combination, an electric circuit including a drop device adapted to open and close said circuit and constituting a guide for a strand of yarn, a plurality of guides for said yarn, a lever adapted to engage said drop device, a pivot for said lever, a weight adapted to be detachably fastened to said lever at one side of said pivot and a guide for said yarn mounted on said lever, whereby when under abnormal tension said lever may be rocked by said yarn to move said drop device to close said circuit.

10. 8. A circuit closing device having, in combination, an electric circuit including two contacts, a drop device adapted to engage said contacts and close said circuit, said drop device constituting a guide for a strand of yarn, guides for said yarn on opposite sides, respectively, of said drop device, one of said guides being adjustable vertically whereby, through said yarn, said drop device may be adjusted relatively to said contacts, a stop adapted to engage said drop device to limit the distance to which it may be moved away from said contacts and means actuated by an abnormal tension on said yarn adapted to move said stop to bring said drop device into engagement with said contacts.

15. 9. A circuit closing device having, in combination, an electric circuit including a drop device adapted to open and close said circuit and constituting a guide for a strand of yarn, a plurality of guides for said yarn and means normally independent of said drop device and adapted to be actuated by an abnormal tension on said yarn to engage said drop device and move it to close said circuit.

20. 10. A circuit closing device having, in combination, an electric circuit including a drop device adapted to open and close said circuit and constituting a guide for a strand of yarn, a plurality of guides for said yarn, a lever adapted to engage said drop device and a guide for said yarn mounted on said lever whereby, when under abnormal tension said lever may be rocked by said yarn to move said drop device to close said circuit, the relative location of said parts being such that when said drop device is moved downwardly to close said circuit said lever yarn guide will be moved to feed yarn thereto.

25. 11. A circuit closing device including an electric circuit, a drop device adapted to open and close said circuit and constituting a guide for a strand of yarn, a yarn mass, a yarn scraper interposed between said drop device and yarn mass and means adapted under abnormal tension to move said drop device to close said circuit in combination with a knitting machine and a stop motion mechanism adapted to be actuated by the closing of said circuit to stop said knitting machine.

12. A knitting machine having, in combination, a series of needles, a support therefore, a mass of yarn, a stop motion mechanism including a tripper, an electric circuit including an electromagnet adapted, when said circuit is closed, to actuate said tripper to release said stop motion mechanism, said electric circuit embodying a pair of contacts and a drop device constituting a guide for 5
 10 yarn adapted to engage said contacts and close said circuit and guides whereby said yarn, when under tension, is adapted to hold said drop device out of engagement with said contacts, one of said guides constituting
 15 a yarn scraper and located between said drop device and yarn mass.
13. A knitting machine having, in combination, a series of needles, a support therefore, a mass of yarn, a stop motion mechanism including a tripper, an electric circuit including an electromagnet adapted, when said circuit is closed, to actuate said tripper to release said stop motion mechanism, said electric circuit embodying a pair of contacts 20
 25 and a drop device constituting a guide for yarn adapted to engage said contacts and close said circuit, guides whereby said yarn, when under tension, is adapted to hold said drop device out of engagement with said
 30 contacts, one of said guides constituting a yarn scraper and located between said drop device and yarn mass and means operated by said yarn when under abnormal tension to move said drop device into engagement, 35
 40 with said contacts.
14. A circuit closing device having, in combination, an electric circuit including two contacts, a U-shaped drop wire, the legs of which are adapted to engage said contacts and close said circuit, the closed end of said U-shaped wire having a bend therein constituting 45
 50 a guide for a strand of yarn, a stop adapted to be engaged by the closed end of said U-shaped wire to limit the distance to which said wire may be moved away from 45
 55 said contacts and means actuated by an abnormal tension on said yarn adapted to move said stop to bring the legs of said U-shaped wire into engagement with said contacts. 50
15. A circuit closing device having, in combination, an electric circuit including a drop device adapted to open and close said circuit and constituting a guide for a strand of yarn, a plurality of guides for said yarn, cutting instrumentalities and means actuated by an abnormal tension on said yarn adapted to engage said drop device and move it to close said circuit, said means also adapted to actuate said cutting instrumentalities 60
 65 to sever said yarn.
16. A circuit closing device having, in combination, an electric circuit, including a drop device adapted to open and close said circuit and constituting a guide for a strand of yarn, a plurality of guides for said yarn, a stationary cutter blade, a lever adapted to engage said drop device, a guide for said yarn mounted on said lever, and a movable cutter actuated by said lever adapted to contact with said stationary cutter to sever said yarn, whereby under abnormal tension said lever may be rocked by said yarn to sever the same and move said drop wire to close 70
 75 said circuit.

In testimony whereof I have hereunto set my hand in presence of two subscribing witnesses.

WILLIAM W. BURKE.
